DRAFTING APPARATUS OF TEXTILE SPINNING AND ANALOGOUS MACHINES

John Barker Arundale, Accrington, Lancashire, and James Jackson Haythornthwaite, Huncoat, Lancashire, England, assignors of one-third to Howard and Bullough Limited, Accrington, England

Application April 27, 1950, Serial No. 158,518
In Great Britain May 4, 1949

9 Claims. (Cl. 19—134)

1

This invention is directed to the adjustment of the relative spacing of the rollers of the drafting apparatus of a textile spinning or analogous machine and its object is to provide means by which such adjustment can be effected conveniently when required by a change in the staple length of the fibrous material under treatment in the machine.

According to the invention drafting apparatus of a textile spinning or analogous machine has the drafting rollers which require adjustment of their relative spacing mounted in sets of bearing blocks slidably carried upon guides extending across the roller stand, each such bearing block having a female screw thread adapted to co-operate with an individual lead-screw supported parallel to the guides and capable of rotation to traverse the bearing block to the requisite position.

According to a further feature of the invention the bearing blocks for the front roller are fixed in relation to the stand and serve as supports for the lead-screws.

In order that the invention may be more readily understood reference will be made to the accompanying drawings which illustrate by way of example a preferred embodiment thereof.

In the drawings:

Fig. 1 is an elevational view of drafting apparatus provided with means for the adjustment of the relative spacing of the drafting rollers.

Fig. 2 is an elevational view of an alternative arrangement of drafting apparatus of which the roller stand is nearly vertical.

Fig. 3 is an elevational view of Fig. 2 looking in the direction of the arrow X.

Fig. 4 is a diagrammatic fragmentary view of an arrangement showing means for imparting a common drive to the lead-screws, and indicating means for denoting the setting of the bearing blocks.

In Fig. 1 the invention is shown applied to the drafting apparatus of a ring spinning machine of conventional form, in which the roller stand 1 is inclined rearwardly at an angle which is not substantially greater than 45° to the horizontal. The roller stand 1 is provided with an upstanding part 2 which acts as a bearing block for the front roller 3. In the embodiment of the invention illustrated four lines of drafting rollers 3, 4, 5 and 6 are provided, and these are supported respectively in sets of bearing blocks 2, 7, 8 and 9. The bearing blocks 7 and 9 of one set are slidably mounted in a guide incor-

2

porated in the base 10 of the roller stand, whilst the bearing block 8 is slidably mounted on the bearing block 7 which is formed with an extended base incorporating a guide 11 for receiving the block 8.

The relative spacing of the bearing blocks 7, 8 and 9 is adjustably controlled by means of lead-screws 12, 13 and 14. These lead-screws are rotatably mounted in the upstanding part 10 2 of the roller stand but are prevented from axial movement in relation thereto.

The bearing blocks 7, 8 and 9 are each provided with an internal thread with which each lead-screw co-operates, and as can be clearly seen in Fig. 1 the lead-screw 12 engages with the bearing block 7, the lead-screw 13 with the bearing block 8 and the lead-screw 14 with the bearing 9. The block 7 is provided with clearance holes for the lead-screws 13 and 14 and a clearance hole for the lead-screw 14 is also provided in the block 8. The lead-screws are each provided with heads fashioned to receive a spanner, key, screw-driver or other tool by which they may be rotated individually for the purpose of adjustment. It may also be desirable to prevent unauthorised alteration of the roller spacings by shrouding the ends of the lead-screws by means of a removable plate (not shown), or by arranging that they can only be adjusted by means of a key of unusual form which would not normally be accessible to persons not authorised to change the roller spacings.

Whilst the lead screws have been shown one above the other with the longest at the bottom and the shortest at the top the relative position of the lead-screws is not important and their order could conveniently be reversed. Moreover, instead of being arranged one above the other they could equally well be arranged side by side in the manner shown in Figs. 2 and 3.

In the alternative arrangement of drafting apparatus shown in Figs. 2 and 3 the roller-stand is nearly vertical or inclined at an angle substantially exceeding 45° from the horizontal. In this arrangement it makes for greater accessibility of the lead-screws, when adjustment of the roller spacing is required, to arrange the lead-screws so that they project through fixed abutments above the back or feed rollers. Referring to Figs. 2 and 3 the stand 15 is provided with nearly vertical guides 16 upon which each set of roller bearing blocks 17 and 18 are adapted to slide. The lower or front roller is supported in a projecting portion 19 of the stand 15.

3

The adjustment of the relative spacing of the roller bearing blocks 17 and 18 is respectively effected by lead-screws 20 and 21 arranged side by side and rotatably mounted in a fixed abutment 22 above the back or feed rollers. The lead-screws are prevented from axial movement in relation to the roller stand 15 and engage with threads in the blocks 17 and 18 to adjust the spacing of each block when the corresponding lead-screw is rotated. The bearing block 17 is provided with a clearance hole for the lead-screw 21 and the adjustment of the blocks is effected in a manner similar to that described with reference to Fig. 1.

After a convenient relative spacing of the bearing blocks 17 and 18 has been effected, the said blocks may be clamped to the stand 15 by means of the clamping screws 23 and 24 which engage with nuts 25 and 26 on the inside of each guide 16. An indication of the setting of a block with reference to a datum position may be denoted by the relative position with reference to a fixed indicator 27, of a graduated collar 28 upon the lead-screw pertaining thereto.

In Fig. 4 mechanism is shown for adjusting all the bearing blocks relating to one roller simultaneously. In the drawing two pairs of lead-screws are shown, the lead-screws comprising one pair being designated 29 and 30 and those comprising the other pair being designated 31 and 32. All four lead-screws are rotatably mounted in up-standing abutments 33 and 34 fixed to the roller stand (not shown).

Each lead-screw extends beyond the abutments 33 and 34 and engages with co-operating bearing blocks (not shown) adapted to support between them a roller or part thereof. The lead-screws 29 and 30 which co-operate with the bearing blocks of one roller are respectively provided with worm wheels 35 and 36 which engage with a worm 37 adapted to be rotated by a crank 38 through gearing 39. Similarly the lead-screws 31 and 32 which engage with the bearing blocks of another roller are respectively provided with worm wheels 40 and 41 which engage with a worm 42 adapted to be rotated by a crank 43 through gearing 44. The cranks 38 and 43 are provided with pointers 45 and 46 which co-operate with graduated discs 47 and 48 to indicate the setting of the corresponding bearing blocks.

In operation when the crank 38 is rotated the worm 37 rotates the lead-screws 29 and 30 simultaneously, and effects an adjustment of the corresponding pair of bearing blocks. The crank 43 serves to rotate the lead screws 31 and 32 in a similar way.

The adjusting principle of Fig. 4 may be applied equally to a structure like that of Fig. 1 or a structure like that of Figs. 2 and 3.

What we claim as our invention and desire to secure by Letters Patent is:

1. In drafting apparatus of a textile spinning or analogous machine, having drafting rollers which require adjustment of their relative spacing mounted in sets of bearing blocks slidably carried upon guides that extend lengthwise of a

4

roller stand, the combination with a plurality of adjustable bearing blocks of individual lead screws each threaded into a single one of the blocks only for adjusting that block relative to the others, and a common stationary support in which all the screws are secured with capacity for rotary but not axial movement, each bearing block other than the one most remote from said common stationary support being formed to provide clearance for the adjusting screw of each block more remote than itself from the stationary support.

2. A structure as claimed in claim 1 wherein the lead-screws co-operating with the set of blocks referred to are arranged one above the other.

15 3. A structure as claimed in claim 1 wherein the lead-screws co-operating with the set of blocks referred to are arranged side by side.

4. A structure as claimed in claim 1 wherein indicating means is associated with each lead-screw to denote the setting of the corresponding bearing block with reference to a datum position.

5. A structure as claimed in claim 1 in which each of the lead screws referred to is operable independently of the others to adjust the bearing block individually controlled by it independently of the other bearing blocks referred to.

6. A structure as claimed in claim 1 in which each roller is carried in a plurality of bearing blocks, each controlled by its individual lead screw, and in which a separate common operating means is provided for the lead screws that effect the adjustment of each roller.

7. A structure as claimed in claim 1 in which each roller is carried in a plurality of bearing blocks, each controlled by its individual lead screw, and in which a separate common operating means is provided for the lead screws that effect the adjustment of each roller, and in which indicating means is provided in association with each common operating means to denote the setting of the respective rollers with reference to a datum setting.

8. A structure as set forth in claim 1 in which the common stationary support for all the lead screws constitutes a bearing block for supporting a non-adjustable roller.

9. A structure as set forth in claim 1 in which provision is further made of a non-adjustable roller and a stationary bearing support therefor, and in which the common stationary support for the lead screws is located at the opposite side of the adjustable bearing blocks from said non-adjustable roller.

JOHN BARKER ARUNDALE.
